UNITED STATES PATENT OFFICE

166,610

GARMENT HANGER

Alexander Kerby, Cleveland Heights, Ohio

Application October 11, 1950, Serial No. 12,520

Term of patent 14 years

(CL. D80—8)

To all whom it may concern:

Be it known that I, Alexander Kerby, a citizen of the United States, residing at Cleveland Heights, county of Cuyahoga, and State of Ohio, have invented a new, original, and ornamental Design for a Garment Hanger, of which the following is a specification, reference being had to the accompanying drawings, forming a part hereof.

Fig. 1 is a top plan view of a garment hanger, showing my new design; Fig. 2 is a front elevational view of the hanger; Fig. 3 is an end elevational view of the hanger; Fig. 4 is a rear elevational view of the hanger.

I claim:

The ornamental design for a garment hanger, as shown.

ALEXANDER KERBY.
